(57) **CLAIM**

The ornamental design for a collapsible plastic hook for a plastic garment hanger, as shown and described.

DESCRIPTION

FIG. 1 is a front perspective view of a collapsible plastic hook for a plastic garment hanger hook showing my new design;

FIG. 2 is a front elevation view thereof;

FIG. 3 is a right side elevation view thereof;

FIG. 4 is a rear elevation view thereof;

FIG. 5 is a left side elevation view thereof;

FIG. 6 is an enlarged partial view thereof taken from the broken circle shown in FIG. 2;

FIG. 7 is a front perspective view thereof showing the collapsible plastic hook in a collapsed position;

FIG. 8 is a top view of the collapsible plastic hook in the collapsed position;

FIG. 9 is a front elevation view of the collapsible plastic hook in the collapsed position;

FIG. 10 is a rear elevation view of the collapsible plastic hook in the collapsed position;

FIG. 11 is an enlarged sectional view taken along lines 11-11 of FIG. 10; and,

FIG. 12 is an enlarged partial perspective view of the collapsible plastic hook in the collapsed position taken from the broken circle shown in FIG. 7.

The broken lines shown represent unclaimed subject matter and form no part of the claimed design.
